Atty.

UNITED STATES PATENT OFFICE.

HARRY F. ANDERSON, OF MARION, INDIANA, ASSIGNOR OF ONE-HALF TO JAMES BOYCE, OF LAKETON, MICHIGAN.

SIGN.

Application filed October 6, 1924. Serial No. 741,800.

Interiorly illuminated signs are commonly formed of so-called glass letters, each letter consisting of a rectangular plate having a letter or other character embossed thereon. The entire letter or panel is molded or otherwise formed of opal glass or other suitable translucent material. In order to give the character strokes the necessary definiteness or prominence, the portion of the plate surrounding the character strokes is covered by means of a sheet-metal stencil.

There is another class of signs in which the glass character is mounted in a suitable translucent background of contrasting color made up of pieces of glass held together by lead. Such leaded glass signs are relatively expensive on account of the considerable amount of skilled labor required in producing the leaded glass.

The present invention has reference to both of the above-mentioned classes of signs. One object of the invention is to obtain the pleasing effect of a leaded glass sign without the expense involved in the use of leaded glass. Other objects are to eliminate the expense of the sheet-metal stencil heretofore employed, to impart added strength to the letter, and to protect the inner side of the character from an accumulation of dust.

In the accompanying drawings, Figure 1 is a perspective view of an electric sign embodying the features of this invention.

Fig. 2 is a face view of one of the panels or sign units comprised in the sign.

Fig. 3 is a sectional view taken in the line of 3-3 of Fig. 2.

Referring first to Figs. 2 and 3, each panel or sign unit comprises a backing 1 which may be of transparent colorless glass; a letter or other character 2 molded of opal glass or the like, the strokes or parts of the letter or other character being convexo-concave, as clearly shown in Fig. 3; and a background 3 surrounding the letter or other character and of the same height and width as the backing 1. The background 3 is made up of a number of pieces of glass 3^a fitted together to occupy the space around the letter. The pieces 3^a are preferably of translucent glass and of a color contrasting with that of the letter 2, as, for example, a mottled blue. The letter 2 and the pieces 3^a may be secured to the backing 1 by means of a suitable cement 4.

Letters or sign units such as the one described may be employed in making up signs in various ways. In Fig. 1 I have shown a sign casing 5, the front of which constitutes a frame 6 having a plurality of rectangular openings 7 to receive letters or sign units. The openings 7 are somewhat smaller than the sign units, and thus the front wall or frame 6 overlaps the edges of each sign unit. The sign units may be secured in place within the casing 5 in any preferred manner.

It will be apparent that a sign constructed as herein disclosed has the appearance of being composed of embossed letters mounted in leaded glass panels. A very attractive effect is thus obtained at relatively small cost.

It will be noted that the opacity or translucency required to define the letter and give it the necessary prominence is obtained by means of the translucent background 3 and without the use of sheet-metal stencils, such as have heretofore been commonly used in signs of the general type herein referred to.

The glass plate 1 imparts strength and rigidity to the unit or panel and also keeps dust and dirt out of the concave side of the letter 2.

When the sign is illuminated, the lines of cement 4 produce substantially the same optical effect as the lead in leaded glass. The appearance of leaded glass and the function of securing the letter 2 and pieces 3 to the backing 1 are thus obtained at a small fraction of the cost of leaded glass.

I claim as my invention:

1. A panel or unit for signs having, in combination, a backing plate of transparent colorless glass, a character of convexo-concave cross-section made of translucent glass, a background formed of pieces of translucent glass of a color contrasting with that of the character, and lines of cement securing the character and the pieces forming the background to the backing plate, said background being of substantially the same outside dimensions as said backing plate.

2. A panel or unit for signs having, in combination, a glass backing plate, a character of convexo-concave cross-section made of translucent glass, a background formed of pieces of translucent glass of a color contrasting with that of the character, and lines

of cement securing the character and the pieces forming the background to the backing plate.

3. A panel or unit for signs having, in combination, a glass backing plate, a character of convexo-concave cross-section made of translucent glass, a background of translucent glass of a color contrasting with that of the character, and lines of cement securing the character and the background to the backing plate.

4. A panel or unit for signs having, in combination, a glass backing plate, a character of convexo-concave cross-section made of translucent glass, a background of translucent glass of a color contrasting with that of the character, said character, background and backing plate being secured together.

5. A sign comprising a casing, the front wall of which has an opening therein, a sign unit exposed through said opening, said sign unit comprising a glass backing plate of the

same general outline as said opening, a character of convexo-concave cross-section made of translucent glass, and a translucent background of a color contrasting with that of the character, said character, background and backing plate being secured together. 25

6. A sign comprising a casing, the front wall of which has a plurality of rectangular openings therein, a sign unit exposed through each of said openings, each of said sign units comprising a rectangular transparent glass backing plate, a character of convexo-concave cross-section made of translucent glass, and a translucent background covering the exposed portion of the backing plate, and of a color contrasting with that of the character, said character, background and backing plate being secured together. 30 35 40

In testimony whereof, I have hereunto affixed my signature.

HARRY F. ANDERSON.
